UNITED STATES PATENT OFFICE.

CHARLES BAILLAIRGE, OF QUEBEC, CANADA.

DESIGN FOR THE ARRANGEMENT OF GEOMETRICAL FORMS.

Specification forming part of Design No. 5,408, dated December 12, 1871.

To all whom it may concern:

Be it known that I, CHARLES BAILLAIRGE, of Quebec, in the Province of Quebec and Dominion of Canada, have invented a new and original Design for a Stereometrical Tableau, of which the following is a specification:

The photographic illustration represents a face view of my new stereometrical tableau.

This invention relates to a new arrangement of stereometrical forms and bodies on a board or plate in the succession represented in the photograph.

It will be noticed that there are two hundred such models, each different from the other, arranged on a board of convenient size. Among

them will be observed right and inclined prisms, prismoids, cylinders, cylindroids, pyramids, cones, spheres, and their respective sections, and other forms of stereometrical figures, the selection being best adapted for school purposes and colleges.

I claim as my invention—

The design for a stereometrical tableau, as shown.

CHARLES BAILLAIRGE.
